UNITED STATES PATENT OFFICE.

LOUIS B. HASBROUCK, OF ELMIRA, NEW YORK, ASSIGNOR TO ECLIPSE TEXTILE DEVICES, INC., OF ELMIRA, NEW YORK, A CORPORATION OF NEW YORK.

BOBBIN SUPPORT.

Continuation of and substitute for applications Serial No 140,430, filed October 9, 1926, and Serial No. 149,050, filed November 18, 1926. This application filed May 26, 1928. Serial No. 280,675.

This invention relates to bobbin supports and aims to provide an improved means for mounting roving bobbins on the creels of spinning frames and the like.

5 The present application is a continuation of and substitute for my two co-pending applications, Serial No. 140,430, filed October 9, 1926, and Serial No. 149,050, filed November 18, 1926, and is filed for the purpose of 10 presenting the invention described in said applications in a single application.

In the operation of a spinning frame, any 15 resistance to the rotation of the creel bobbins from which the rovings are drawn causes a backdraft on the rovings in addition to the intended draft of the drawing rolls, which has the effect of attenuating, or reducing the "count" of, the yarn being spun. While it is desirable that such backdraft be made as 20 slight as possible, and various bobbin mountings have been devised or proposed with this in view, it is, I have ascertained, much more important that such backdraft as exists be made uniform, both on different rovings of 25 the same frame, and on each roving throughout the time that it is being unwound from a bobbin. It is only by securing such uniformity in the backdraft that the yarns spun on the different spindles of the frame may be 30 made of exactly the same count, and each yarn may be made uniform throughout its length. The securing of this important result is an object attained by my invention.

Another object attained by the invention 35 is to make possible changing the bobbins in the back row of the creel without removing those in the front row.

Bobbin supports heretofore used have had 40 spaced bearings or equivalent means for retaining the axis of each bobbin in a fixed position during the unwinding. I have discovered that such bearings are a cause of irregular backdraft, owing to the fact that the lateral strains on the bobbins (which result 45 not only from the pull of the rovings but also from eccentricity of the weight of the bobbin or more particularly of the mass of roving wound thereon) are different in different bobbins, and, in each bobbin, vary during the 50 unwinding of the roving thereon. The variation in these lateral strains causes irregular friction in bearings which resist lateral movement of the bobbin. I have discovered, fur-

ther, that this disadvantage may be eliminated by relying solely on the weight of the 55 bobbin to prevent objectionable lateral movement of the bobbin during unwinding.

My invention, which is based on these discoveries, provides for supporting a bobbin well above its center of gravity, and leaving 60 it free to tip as well as to rotate about its support. A bobbin-supporting device embodying the invention in the form which I consider most desirable consists of a fixed part 65 attached to the creel of a spinning frame, or its equivalent, and a rotary part adapted to engage a bobbin near one of its ends; and a combined bearing and universal joint connecting the fixed and rotary parts. My invention is, however, not limited to this most 70 desirable embodiment thereof.

In order that the invention may clearly be understood, I will describe in detail the embodiments thereof, which are shown in the accompanying drawings, in which:

75 Figs. 1, 2 and 3 are axial sections of three bobbin supports each embodying the invention;

Fig. 4 is a transverse sectional elevation of the upper part of a spinning frame of usual 80 construction, showing the creel provided with bobbin supports of the form shown in Fig. 1;

Fig. 5 is a side elevation of part of the creel, illustrating the changing of a bobbin in the inner row without removing the bobbins of the outer row;

Fig. 6 is an axial section of another form of bobbin support embodying the invention; and

Fig. 7 is a section on the line 7—7 of 90 Fig. 6.

The bobbin support shown in Fig. 1, which I regard as the best form of the invention, includes a fixed supporting member 10 and a rotary bobbin-engaging member 12 connected by a single bearing 11. The fixed and rotary parts 10 and 12 are provided with opposed bearing surfaces 13, 14 which in this instance serve as races for bearing balls 15 interposed between them. One of the bearing surfaces, in this instance the fixed surface 13, is spherically curved, with its center of curvature at a point 16, located substantially on the axis B¹ of a bobbin B carried by the rotary part 12 and materially above the middle B² of this bobbin. The other bearing 95 100 105

surface, 14, has the form of an ordinary ball race.

The parts of the bobbin support shown in Fig. 2 correspond to those of the bobbin support shown in Fig. 1, and are correspondingly numbered, but in this instance it is the movable bearing surface 14' which is spherically curved about a center 16', while the fixed bearing surface 13' has the form of an ordinary ball race.

Corresponding parts are found in the bobbin support shown in Fig. 3, but in this instance both the bearing surfaces 13² and 14² are spherically curved, and they are in direct contact with each other, as no bearing balls are used.

It is apparent that in each of the modifications described, the bearing is also a universal joint constraining the bobbin against movement at one point only, so that it is free to tip about this point in any direction. Since this point is near one end of the bobbin, the bobbin hangs with its axis vertical, or nearly so, but tips slightly under the influence of any lateral strains. But, such tipping in no way affects the operation of, or the resistance upon, the bearing which carries the bobbin. Consequently a variation in lateral strains on the bobbin causes no irregularity in the resistance to the rotation of the bobbin and no irregularity in the back-draft upon a roving drawn from it.

Figs. 6 and 7 show a bobbin support embodying the invention in a simplified, but I believe a less satisfactory, form. In this instance, the bobbin-engaging member 12³ is suspended from a single ball bearing 11³, as in the supports shown in Figs. 1 and 2, but the bearing surfaces or races 13³, 14³ of the bearing 11³ are of the conventional form, so that the bearing does not act as a universal joint. Nevertheless, as the bearing 11³ is the sole connection between the fixed supporting member 10³ and the bobbin-engaging member 12³, the member 12³ and the bobbin are free to tip about the bearing.

The particular construction of the bobbin supports illustrated is as follows:

In Fig. 1 the fixed member 10 includes a bolt 20 having a head 21 at its upper end and a nut 22 at its lower end. The bolt may extend through a creel board C with its head against the upper surface of the board and its lower end projecting below the lower surface thereof. On the bolt are mounted a dust cap 23, a spacing washer 24, and a spacing sleeve 25, which are locked against the lower surface of the creel board by the nut 22, and a bearing member resting on the nut and providing the bearing surface 13. The rotary member 12 consists of a sleeve having its upper edge turned in to provide a curved lip 26, which provides the bearing surface 14. It should be noted that sufficient clearance is allowed between the fixed and movable parts,

and particularly between the dust cap 23 and the lip 26, to permit the sleeve to tip freely about the point 16.

The sleeve 12 is provided with a resilient gripping means to engage the inner surface of the bobbin and hold it on the sleeve. Such means consist of two flat expansion springs 27 located within the sleeve below the nut 22, and provided with external bosses 28 which project through holes 29 in the sleeve. The sleeve has also an external annular rib 30 which serves to limit the extent to which a bobbin may be pushed upon the sleeve, by engaging the small internal shoulder B³ with which roving bobbins B are provided near their upper ends. At the same time, the peripheral surface of the rib 30 engages the enlarged bore of the bobbin above this shoulder, and thus cooperates with the gripping means holding the bobbin upon the sleeve.

It should be noted that the bobbin support which has been described may be manufactured at small cost because of the small number of parts of which it is composed, and because all of these parts, except those which are standard machine parts, may easily be made as stampings.

The construction of the bobbin support shown in Fig. 2 is identical with that of the support shown in Fig. 1, except for such changes in the form of the parts as are necessary to effect the interchange in the form of the bearing members hereinbefore described. The construction of the bobbin support shown in Fig. 3 is apparent from the drawing.

The construction of the bobbin support shown in Figs. 6 and 7 is identical with that shown in Fig. 1, except that the bolt 20³ is inverted, so that it has its head 21³ at its lower end and a nut 22³ at its upper end; and an ordinary ball race 13³ is used instead of the spherically curved bearing surface 13.

The use of the bobbin supports shown in Figs. 1 and 2 is illustrated in Figs. 4 and 5, which show the creel of a spinning frame provided with such supports. The supports and bobbins which they carry depend from the creel boards, and sufficient clearance is allowed between the lower ends of the bobbins and the creel board below them to facilitate cleaning the upper surfaces of the creel boards to remove the fly which tends to collect on them. In this connection, it should be noted that the only parts of the bobbin supports which project above the upper surfaces of the creel boards are the rounded heads 21 of the bolts, which in no way interfere with such cleaning.

Removal of the bobbins from the supports and replacement of the bobbins thereon is accomplished easily and quickly. To remove a bobbin, it is necessary only to pull it downward to free its upper end from the spring

grips and the sleeve of its support. A bobbin is replaced by pushing its upper end up around the sleeve until it engages the shoulder 30. In this operation, the sleeve is moved 5 upward to some extent, but its movement is limited by engagement with the dust cap, or with the creel board if no dust cap is used, so that the bobbin may readily be pushed upon it.

10 Owing to the free tipping of the sleeves, it is possible to change the bobbin on a support in the inner row of the creel without removing any of the bobbins in the outer row. This is accomplished, as shown in Fig. 4, merely 15 by tipping two of the bobbins in the outer row sufficiently to permit the passing of another bobbin between them.

The removal and replacement of the bobbins upon supports such as those shown 20 in Fig. 3 is less convenient, since in order to remove a bobbin from the sleeve 12², it is necessary to lift the support 10² from the creel board into which its lower end projects.

What I claim is:

25 1. The combination with the creel of a spinning frame and the like and a roving bobbin, of means for supporting the bobbin on the creel providing a bearing which is located well above the center of gravity of the bobbin, and with respect to which the bobbin rotates and about which it is free to tip.

30 2. A bobbin support for the creels of spinning frames and the like comprising a bearing having cooperating bearing surfaces, means supporting said bearing and holding one of its bearing surfaces against rotation, and means for so suspending a bobbin from said bearing that it is free to rotate and to tip about the fixed bearing surface of said bearing.

35 3. The combination with the creel of a spinning frame and the like and a bobbin whose center of gravity is at one side of its center line, of a bobbin support comprising a fixed member secured to the creel and providing a fixed bearing surface, and means for so suspending one end of the bobbin from said fixed bearing surface that it is free to rotate and to tip about the fixed bearing surface, so that it hangs from the fixed bearing surface with its center of gravity directly under the center of the fixed bearing surface.

40 4. A bobbin support for the creels of spinning frames, comprising a fixed supporting member, a rotary bobbin-engaging member, said members being formed to provide a single bearing between them, located above the center of gravity of the bobbin, which permits the rotary member to tip about the axis of the fixed member.

45 5. A bobbin support for the creels of spinning frames, comprising a ball bearing, means for supporting said ball bearing, and means for suspending the bobbin from said ball

bearing arranged to leave the bobbin free to tip about the bearing.

6. A bobbin support for the creels of spinning frames, comprising a fixed member, a bearing thereon, a rotary bobbin-engaging member suspended from said bearing, said fixed and rotary members being formed to permit the rotary member to tip about the axis of the bearing.

7. A bobbin support, comprising a sleeve 75 having an inturned lip at its upper end, a fixed stud extending into said sleeve and terminating therein, an upturned ball race on said stud, and bearing balls between the race and the lip of the sleeve.

8. The combination with a bobbin support, as claimed in claim 7, of a dust cap mounted on said stud above the sleeve, and having a downwardly curved circumferential lip overlying and spaced from the inturned lip of the 85 sleeve.

9. A bobbin support, comprising the combination with a set of bearing balls, of a fixed member supporting the balls, and a rotary bobbin-engaging member having a ball race 90 resting on the balls and free to be lifted from them; and means normally spaced from the rotary member for limiting the upward movement thereof.

10. A bobbin support, providing a bearing 95 supporting the bobbin located above its center of gravity and constraining it against movement at one point only, so that it is free to tip about said point in any direction.

11. A bobbin support, comprising a fixed 100 part, a rotary part detachably engaging the bobbin, and a bearing connecting said parts, located above the center of gravity of the bobbin, and formed to permit free tipping of the bobbin without change in the frictional 105 resistance of the bearing.

12. A bobbin support, comprising fixed and rotary parts providing opposed bearing surfaces at least one of which is spherically 110 curved with its center of curvature substantially on the axis of the bobbin and materially above the middle of the bobbin.

13. A bobbin support, comprising fixed and rotary parts providing opposed ball races, one of which has a spherically curved surface 115 with its center of curvature substantially on the axis of the bobbin and materially above the middle of the bobbin, and bearing balls interposed between said races.

14. In a creel, the combination with a creel board, of a bobbin support comprising a bolt 120 having a rounded head and extending through the creel board from the upper side thereof, and a bobbin-engaging member mounted on the lower projecting end of said bolt, so that the only part of the support projecting above the upper surface of the creel board is the rounded head of the bolt.

15. A bobbin support for the creels of spinning frames and the like, comprising a sup- 130

porting part supported by the creel and a bobbin-engaging part, said parts being formed to provide a universal joint which is the sole connection between them and is located above the center of gravity of a bobbin carried by the support.

16. A bobbin support for the creels of spinning frames and the like, comprising a supporting part secured to the creel and a bobbin-

engaging part, providing opposed engaging surfaces forming the sole connection between them and at least one of which is spherically curved with its center of curvature substantially on the axis of the bobbin and materially above the middle of the bobbin.

In testimony whereof I have hereunto set my hand.

LOUIS B. HASBROUCK.
